UNITED STATES PATENT OFFICE

2,324,392

MEANS FOR FEEDING LIQUEFIED GAS-OZONE FUEL TO INTERNAL COMBUSTION ENGINES

Alva K. Hinchman, Bryn Mawr, Pa., assignor to Ozone Gas Combustion Co., Inc., a corporation of Delaware

Application June 12, 1941, Serial No. 397,674

1 Claim. (Cl. 48—180)

My invention relates to a new and useful method of producing a liquefied gas-ozone fuel and means for feeding it to an internal combustion engine.

One object of the present invention is to mix ozone with liquefied gas to produce a highly explosive engine fuel having a high octane rating, which fuel is inexpensive to produce and has little or no decomposing effect on the engine lubricating oil.

Another object of this invention is to provide an unique mixing valve for introducing ozone into the liquefied gas and for feeding the resultant fuel to an internal combustion engine.

Another object of the invention is to utilize the liquefied gas, prior to being incorporated with the ozone, as the cooling agent for the engine.

Another object of the invention is to provide a pressure regulator in the liquefied gas line which functions as a supercharger regulator in the apparatus.

Another object of the invention is to provide means for heating the fuel, if desired, prior to said fuel being fed to the engine.

A further object of the invention is to provide apparatus for passing liquefied gas from a storage receptacle through a pressure regulator, to and through a compartment for the cooling agent generally formed by a jacket about the engine cylinder or cylinders, thence to the mixing valve; to provide apparatus for passing ozone from a generator to and through a special feed device, preferably as a part of the mixing valve, to said mixing valve and finally, through a throttle, to the engine.

With the above and other objects in view, this invention consists of certain details of construction and combination of elements hereinafter set forth and then designated by the claim.

In order that those skilled in the art to which this invention appertains may understand how to make and use the same, I will describe its construction, referring by numerals to the accompanying drawings forming a part hereof, in which—

Fig. 1 is a view of the apparatus constituting one part of my invention, the relation of the several elements to one another being illustrated diagrammatically.

Fig. 2 is a similar view with some of the elements in different positions and a number of said elements shown in section and the by-pass left off.

Fig. 3 is an enlarged sectional view of the mixing valve on the line 3—3 of Fig. 2.

Fig. 4 is a side elevation of the mixing valve in the same position as Fig. 3.

5 Fig. 5 is a view thereof looking at it from the left hand side of Fig. 4.

Fig. 6 is a view of the same valve looking at it from the right hand side of Fig. 4.

Fig. 7 is a perspective view of the rotary valve 10 plug or throttle.

Fig. 8 is a view of the apparatus illustrating diagrammatically some of the elements and showing how the products of combustion can be utilized for heating the mixing valve.

15 Fig. 9 is an enlarged cross-sectional view of the hot air pipe to illustrate the fan therein.

In carrying out my invention as herein embodied 10 represents an internal combustion engine of one or more cylinders to which may lead 20 the usual intake manifold 11 or other suitable inlet. The intake of each cylinder is controlled by the usual intake valve 12. Arranged about the cylinder or cylinders is a jacket 13 providing a cooling chamber 14.

25 A source of liquefied gas is provided which may be a tank or other receptacle 15 having a regulator or valve 16 at the outlet, which valve is connected with a pressure regulator 17 to which is attached a pressure gage 18. From the

30 pressure regulator leads a suitable conduit 19 to an inlet 20 to the cooling chamber 14 and said conduit should be of considerable length, but in order to save space of installation said conduit may have a coil 21 formed therein. Another conduit 22 leads from the outlet 23 of the cooling chamber 14 to the mixing valve 24. In order that the liquefied gas may be by-passed around the cooling chamber a valve 25 is interposed in the conduit 19 and preferably a similar valve

35 26 is interposed in the conduit 22 and said valves have a by-pass conduit 27 between them.

The mixing valve 24 comprises a body having at least one expansion chamber 28 with which the conduit 22 is connected, and preferably includes a second expansion chamber 29 in opposed relation to the first mentioned one. Offset to one side is a throttle chamber 30 to and

45 from which lead the opposed inlet and outlet ports 31 and 32 respectively, each of which has a rectangular portion, preferably oblong, at their points of communication with the throttle chamber 30 as shown in Figs. 3 and 4.

50 A duct 33, controlled by an auxiliary needle valve 34, leads from the expansion chamber 28 to a cross duct 35 which in turn leads to the

55

axial center of the throttle chamber 30 and said cross-duct is controlled by the master needle valve 38. Where a second expansion chamber 29 is provided, such chamber has a duct 37 leading therefrom to the cross duct 35 and said duct is controlled by an auxiliary needle valve 38.

The second expansion chamber 29 is to provide for connection with an emergency supply of gas which may be ordinary gasoline. To this end a tank or other suitable receptacle 39 is conveniently located and a conduit 40 leads directly from the receptacle 39 to the expansion chamber 29.

In the throttle chamber 30 is rotatably mounted the cylindrical throttle valve 41, Fig. 7, having a V or wedge shaped aperture 42 extending into the body thereof from the inner end. This aperture 42 extends all the way across the throttle valve body and one of the surfaces forming it is in a plane parallel to the axis while the other surface is oblique to the first mentioned one. When the valve 41 is rotated to cause the oblique line to traverse the oblong portion of the outlet 32 said outlet will be gradually opened or closed as the case may be. Said throttle valve 41 may be rotated in any convenient manner but for purposes of illustration it is shown as provided with a lever 43 on its outer end to which may be attached a pull rod or wire 44 for actuating the valve from a remote location. The movements of the lever and consequently the valve are limited by stops 45 and 46 which may be lugs on the valve casing.

To the inlet side 31 of the mixing valve is connected the outlet of the ozone control valve 47 and forms a unit with the mixing valve. This ozone control valve includes a housing 48 within which is an apertured partition 49 functioning as a valve seat and also dividing the interior of the housing into two compartments 50 and 51. A poppet valve 52 cooperates with the apertured partition or valve seat and has a stem projecting through and slidably mounted in said partition. A spring 53 urges the poppet valve 52 towards a closed position in opposition to suction caused by operation of the engine. In compartment 51 is a butterfly valve 54 having an operating member 55 on the outside of the housing and may also have an indicator or pointer 56 to show at all times the position of said butterfly valve.

An ozone generator 57 is conveniently located relative to the balance of the apparatus and includes a suitable airtight sealed casing or container 58. Within this casing is an outer tubular electrode 59 containing a snugly fitting insulating sleeve 60 of glass or other suitable material.

Within said sleeve 60 is snugly fitted an inner tubular electrode 61 and snugly fitting inside of said inner electrode is an insulating sleeve 62 which may also be of glass but preferably of some other suitable material that might more readily permit the formation of internal threads 63 at both ends thereof.

Screwed into each end of the insulating sleeve 62 is an insulated stuffing box 64 which is exteriorly threaded for this purpose and permits limited longitudinal adjustment of the stuffing box within the sleeve 62.

An exteriorly threaded rod 65 projects through each stuffing box and has threaded connection with the latter to provide for longitudinal adjustment thereof. On the inner end of each rod is a head 66 of slightly smaller diameter than the interior diameter of the sleeve 62 so that the

circumference of said head is spaced from the inner surface of said sleeve 62. Each threaded rod and its head forms a high tension electrode.

A conductor 67 is connected to the inner tubular electrode 61 at one end thereof and to the adjacent high tension electrode, and another conductor 68 is connected to the outer electrode 59 and its adjacent or other high tension electrode.

Another conductor 69 connects one end of the outer electrode 59 with the secondary side of the transformer 70 and still another conductor 71 connects the opposite end of the inner electrode 61 with said secondary side of the transformer 70. The primary side of the transformer is connected by line conductors 72 with a source of electrical energy and said conductors 72 pass through airtight insulators 73 in one wall of the casing or container 57.

An air inlet 74 leads from the exterior of the casing or container 57 and passes through the tubular electrodes 59 and 61 and their insulating sleeves 60 and 62 to a location inside of the inner insulating sleeve 62 between the two stuffing boxes 64, and said air inlet 74 has a suitable air controlling valve 75 interposed therein at any convenient location outside of the casing 57.

Leading from the space within the inner insulating sleeve 62 between the two stuffing boxes and at a distance from the point of entrance of the air inlet 74, is an ozone outlet 76 passing through the tubular electrodes and their insulating sleeves and communicating with the interior of the casing 57. In order to provide means for permitting air to enter the casing or container 57 for mixture with the produced ozone, I provide a secondary or auxiliary air inlet or intake 77 leading only to the interior of said casing or container 57 and said secondary air inlet or intake is controlled by a cock or valve 78.

The interior of the casing or container 57 is in communication with the chamber 56 of the ozone controlling valve 47 through a conduit 79 which may be provided with a pressure gage 80. When the ozone passes through the controlling valve 47 and enters the mixing valve 24, said ozone will mix with and enrich the gas also entering the mixing valve and the fuel thus formed will be drawn from said mixing valve through the conduit 81 to the intake or intakes or intake manifold of the engine 10.

It is advisable, under some conditions, as when operating an engine at high altitudes, such as in the stratosphere, to raise the temperature of the ozone just before entering the mixing valve. This may be accomplished in any suitable or desirable manner, and for convenience of illustration only, I show in Fig. 8 a hot air drum 82 connected with a source of heat, for example, the exhaust 83 of the engine. A hot air pipe 84 runs from said drum 82 to a stove 85 comprising coils of said pipe, a chamber formed by a jacket on the ozone controlling valve 47 or other equivalent means. Of course this heat exchange device can be a part of the inlet structure 31 of the mixing valve or part of both the controlling and mixing valves.

When the heat is not needed it may be shut off by a damper or valve 86 interposed in the pipe 84. In order to agitate the hot air passing through the pipe and keep an even flow thereof, a fan 87, Fig. 9, is installed in said pipe between the damper 86 and the stove or heat exchange element 85. This fan is particularly advantageous where the exhaust products pass directly through the pipe 84 as a by-pass of the exhaust outlet.

In practice, the operation of the apparatus is as follows:

An electric current is caused to flow through the primary of the transformer 70 and thereafter the secondary or high tension induced current feeds into the tubular electrodes 59 and 61 and thence to the high tension electrodes and this high tension current passes from one high tension electrode to the other. During the operation of the electrical portion of the apparatus as above described air or oxygen, preferably the former, is permitted to flow through the inlet 74 into the chamber formed by the inner insulating sleeve 62 and the stuffing boxes, where it is acted upon by the high tension current and converted into ozone which then flows through the outlet 76 into the interior of the casing 57 from where it flows, in due course, through the conduit 79 into the chamber 50 of the ozone controlling valve 47.

At the same time liquefied gas is permitted to flow from the receptacle 15 through the conduit 19 and either through the engine cooling chamber 14 or through the by-pass 27 to the conduit 22 into the mixing chamber 28 of the mixing valve 24. Where this liquefied gas passes through the cooling chamber of the engine, the movement and expansion of said gas will cause its temperature to drop considerably and cool the engine without relying upon the use of the ordinary water or air cooling systems. Under some conditions gas from the emergency tank 39 may be allowed to flow from the tank or receptacle 39 through the conduit 40 to the mixing chamber 29 of the mixing valve 24.

In any case, with the valves properly set, when the engine piston is on its suction stroke a suction action is created in the conduit 81 and the throttle valve chamber 30 back to the chamber 51 of the ozone controlling valve 47 thus drawing a charge or ozone from the chamber 50. As the

ozone passes through the throttle valve chamber it is mixed with gas ejected through the duct 35 into said throttle valve chamber. The flow of the fuel thus produced is controlled by the throttle valve 41 for retarding or accelerating the engine.

Of course I do not wish to be limited to the exact details of construction herein shown and described, as these may be varied within the scope of the appended claim without departing from the spirit of the invention.

Having described my invention what I claim as new and useful is:

In an apparatus of the kind described, of a valve unit including a mixing valve housing 15 having a throttle valve chamber with an inlet and an outlet, a throttle in said chamber and having a wedge shaped notch in its inner end to provide a variable passageway from the inlet to the outlet, said mixing valve housing having an expansion chamber and feed duct leading therefrom to a cross duct all offset to the throttle valve chamber with which said cross duct communicates at the end of the notch in the throttle, a needle valve to control the outlet duct, another needle valve to control the cross duct, a two compartment controlling valve housing connected to the inlet of the throttle valve chamber, a damper valve in the inner compartment, a poppet valve controlling a communication between said compartments, an ozone generator, means for conveying ozone from the generator to the outer compartment of the ozone controlling valve housing, a source of liquefied gas, and means for conveying gas from its source to the expansion chamber of the mixing valve housing.

ALVA K. HINCHMAN.
